UNITED STATES PATENT OFFICE

155,750

DESIGN FOR A COIN CONTAINER

Joseph Taylor, Youngstown, Ohio

Application February 13, 1948, Serial No. 144,458

Term of patent 3½ years

(Cl. D87—3)

To all whom it may concern:

Be it known that I, Joseph Taylor, a citizen of the United States, residing at Youngstown, in the county of Mahoning and State of Ohio, have invented a new, original, and ornamental Design for a Coin Container, of which the following is a specification, reference being had to the accompanying drawing, forming a part thereof.

Fig. 1 is a front elevational view of a coin container, embodying my new design.

Fig. 2 is a top plan view of the coin container; and

Fig. 3 is a side elevational view thereof.

I claim:

The ornamental design for a coin container, as shown.

JOSEPH TAYLOR.
